(57) **CLAIM**

The ornamental design for a machine vision target, as shown and described.

DESCRIPTION

FIG. 1 is a top perspective view of a first embodiment of a machine vision target made in accordance with the subject design.

FIG. 2 is a bottom perspective view thereof.

FIG. 3 is a top view thereof.

FIG. 4 is a bottom view thereof.

FIG. 5 is a left side view thereof.

FIG. 6 is a right side view thereof.

FIG. 7 is a rear view thereof.

FIG. 8 is a front view thereof.

FIG. 9 is a top perspective view of a second embodiment of a machine vision target made in accordance with the subject design.

FIG. 10 is a bottom perspective view thereof.

FIG. 11 is a top view thereof.

FIG. 12 is a bottom view thereof.

FIG. 13 is a left side view thereof.

FIG. 14 is a right side view thereof.

FIG. 15 is a rear view thereof; and,

FIG. 16 is a front view thereof.

The broken lines depict portions of the machine vision target that form no part of the claimed design.

1 Claim, 8 Drawing Sheets
